United States Patent Office.

LOUIS E. O'BRIEN, OF LATROBE, PENNSYLVANIA.

Letters Patent No. 105,591, dated July 19, 1870.

IMPROVEMENT IN CHECK-VALVES.

The Schedule referred to in these Letters Patent and making part of the same.

To all whom it may concern:

Be it known that I, LOUIS E. O'BRIEN, of Latrobe, in the county of Westmoreland and State of Pennsylvania, have invented a certain new and useful Improvement on Check-Valves; and I do hereby declare that the following is a full, clear, and exact description of the construction and operation of the same, reference being had to the accompanying drawing and to the marks and letters thereon, which said drawing forms part of this specification, and shows my invention as used in a feed-water pipe—

Figure 1 thereof being a view by elevation;

Figure 2, a view by vertical section; and

Figures 3 and 4, views of the valve-cage.

In each of these figures where like parts are shown, like marks and letters are used to indicate the parts.

Ordinarily, that portion of the feed-water pipe directly attached to the forcing-pump is connected to the check-valve chamber by flanges and screws, with packing between the flanged surfaces to make a tight joint.

In case of any accident, or whenever, for any reason, it is desirable to reach the check-valve, the detaching of the connection between the forcing-pump part of the pipe, and the check-valve chamber, is slow and tedious, and often causes considerable delay in reaching and remedying whatever difficulty may exist.

My invention has for its object the ready detaching of the feed-pipe from the check-valve chamber, of the easy removal of the valve, its seat, and cage, for cleaning the valve and seat, or for the removal of any cause that may obstruct the free use of the valve.

The forcing-pump portion of the feed-pipe, under my invention, is connected to the check-valve chamber *a* by a joint-piece, *b*, one end of which screws into the feed-pipe and the other end into the chamber.

Within the valve-chamber the check-valve *c*, its

seat, *d*, and cage *e*, are so fitted as to fully and accurately perform their several functions, and yet, when the joint-piece is detached, to be easily and readily removed, cleansed, and repaired, or replaced by other pieces, and quickly refitted in the chamber.

It will readily be seen by examining the drawing how this can be accomplished. Suppose the parts within the valve-chamber to be out of order; the stop or regulator-valve *f* will be screwed down to its seat, *g*, shutting off the communication between the tank, reservoir, or steam-boiler, as the case may be, through the upper portion *h* of the feed-water pipe. The forcing-pump not being in operation, as it may at any moment be thrown out of gear with the engine or other motive power, the joint-piece *b* can, with a few turns of the wrench, be separated from the pipe and chamber, thus allowing access to the valve-chamber and the easy removal of the valve-seat, valve, and cage.

The locomotive engineer will quickly recognize the advantages and facilities which my invention will give him in freeing the feed-water pipe of the engine from sediment and dirt, and relieving it from the many obstructions to which it is subjected, with little if any delay to the train, or interruption to the running of the engine.

What I claim as my invention, and desire to secure by Letters Patent, is—

The joint-piece *b*, in combination with the valve-seat, valve, and cage, arranged within the check-valve chamber, so as to allow of their ready removal from the chamber, as and for the purposes described.

This specification signed this 21st day of May, 1870.

LOUIS E. O'BRIEN.
